U.S. PATENT DOCUMENTS

The ornamental design for a display screen with graphical user interface, as shown and described.

DESCRIPTIOND593,575 S 6/2009 Ball et al.
D640,269 S 6/2011 Chen
8,091,036 B1 * 1/2012 Pavek et al. 715/762
D655,304 S 3/2012 Zaman et al.
D655,712 S 3/2012 Ray et al.FIG. 1 is a front view of a first embodiment of a display screen with graphical user interface showing our new design;
FIG. 2 is another front view thereof;

FIG. 3 is a front view of a second embodiment of a display screen with graphical user interface showing our new design; and,

FIG. 4 is another front view thereof.
The broken line showing of a device in FIGS. 2 and 4 illustrates environment and the remainder of the broken lines in FIGS. 1-4 represent portions of the display screen with graphical user interface; the broken lines, form no part of the claimed design.**1 Claim, 4 Drawing Sheets**(56)
